UNITED STATES PATENT OFFICE.

FRANK SOCHUREK, JR., OF WEST ALLIS, AND JOSEPH SOCHUREK, OF MILWAUKEE,
WISCONSIN.

SPITTOON-HOLDER.

1,092,869.

Specification of Letters Patent.

Patented Apr. 14, 1914.

Application filed May 31, 1913. Serial No. 771,072.

To all whom it may concern:

Be it known that we, FRANK SOCHUREK, Jr., and JOSEPH SOCHUREK, both citizens of the United States, and residents of West 5 Allis, in the county of Milwaukee and State of Wisconsin, and of Milwaukee, in the county of Milwaukee and State of Wisconsin, respectively, have invented certain new and useful Improvements in Spittoon-Holders; and we do hereby declare that the following is a full, clear, and exact description thereof.

Our invention consists in what is herein particularly set forth with reference to the 15 accompanying drawings and pointed out in the claims of this specification, its main object being to provide the floors of railway passenger-cars with stationary stands combined with spring-controlled slidable carriers for removable spittoons, the carriers 20 with the spittoons thereon being normally latched out of the way against spring-resistance under seats of the cars. However, spittoon holders in accordance with our invention may be variously placed.

Figure 1 of the drawings represents a side elevation partly in section of a spittoon-holder in accordance with our invention, and detachable spittoons therewith, the section being indicated by line 1—1 in the next described illustration; Fig. 2, a front elevation of the same partly in transverse section, the section being indicated by line 2—2 in Fig. 1, and Fig. 3, a plan view of a 35 detail of the holder partly in horizontal section.

Referring by numerals to the drawings, 4 indicates a stand intended to be fastened by screws or otherwise to the floor of a rail- 40 way passenger-car under a seat of the same, and the design of the stand may be varied indefinitely. Extending in opposite directions from the stand we show a pair of upper tubular arms 5, but one of these arms 45 and parts in conjunction with the same may be omitted without departure from what is herein claimed.

Each arm 5 is provided with a longitudinal slot 6 engaged by a depending central fin 7 of a horizontal guide-plate 8, and said fin is in rigid connection with a tubular slide 9 engaging said arm. For a portion of its length, the fin is longitudinally notched to be clear of the slide and a stop in the out- 55 ward path of said fin, this stop being shown as a split-ring 10 arranged between a pair

of collars 11 rigid with the adjacent arm. The ends of the ring are laterally offset and fastened together by a bolt and nut or in some other suitable manner.

The outer end of the slide 9 is closed by a plate 12 suitably secured thereto and provided upon its inner side with a beveled lug 13 by which a spring-latch 14, fastened to the adjacent guide-arm 5, is automatically adjusted to engage said plate when said slide is forced back in said arm against the resistance of a spiral-spring 15 that is suitably stopped at its inner end, the stop in the present showing being a partition 16 70 in a single tube centrally secured to the stand 4 to provide the aforesaid arms.

The guide-plate 8 is upturned at its inner end to provide a stop 17 for a slide 18 that engages said plate and is fastened upon the 75 underside of the bottom of a spittoon 19. Another stop 20 is shown in hinge-connection with the plate 12 to be swung over in front of the spittoon when the same is in connection with the herein described holder. 80

The spittoon in connection with the slide 9 may be normally out of the way under a car-seat in front of a passenger occupying another adjacent seat, and being needed, the latch 14 is released by a foot of said passenger to permit of the slide 9 and said spittoon therewith being automatically moved outward clear of the seat first aforesaid by expansive force of the spring 15. Afterward said slide and spittoon may be 90 moved back by foot-pressure against the plate 12 until said plate is again caught by the latch.

The spittoon being in sliding connection with the holder, it may be readily removed 95 for cleaning regardless of the position of its spring-controlled carrier, and a twin-holder similar to that herein shown is intended for location under a car-seat having a reversible back.

Spittoon-holders in accordance with our invention may be arranged under seats in halls, hotel lobbies and elsewhere particularly in places of public resort.

We claim:

1. The combination of a stand for stationary connection with a floor, a guide-arm extending from the stand, a spittoon-carrier in sliding engagement with the arm, a spring arranged to resist retraction of the carrier, 110 and a latch in connection with said arm for engagement with said carrier to hold the

same in retracted position against expansive force of the spring.

2. The combination of a stand for stationary connection with a floor, guide-arms extending in opposite directions from the stand, a spittoon-carrier in sliding engagement with each arm, springs arranged to resist retraction of the carriers, and latches in connection with the arms for engagement with the said carriers to hold the same in retracted position against expansive force of the springs.

3. The combination of a stand for stationary connection with a floor, a guide-arm extending from the stand, a spring-latch in connection with the arm, a spittoon-carrier in spring-controlled sliding engagement with said arm, and a plate attached to the outer end of the carrier for automatic engagement of the latch when said carrier is in retracted position against spring-resistance.

4. The combination of a stand for stationary connection with a floor, a longitudinally slotted tubular guide-arm extending from the stand, a tubular slide engaging the arm, a spiral-spring in contractile and expandible engagement with said arm and slide, a horizontal plate having a notched vertical fin in connection with the slide and having limited play engagement with the arm-slot, the plate being for the support of a removable spittoon; and a latch in connection with

the aforesaid arm for the engagement of said slide to hold the same in retracted position.

5. The combination of a stand, a longitudinally slotted tube in connection with the stand to form guide-arms extending in opposite directions therefrom, a spring-controlled spittoon-carrier in spring-controlled limited play engagement with each arm and a slot therein, and latches in connection with the arms for engagement with said carriers to hold the same in retracted position against spring-resistance.

6. The combination of a stand for stationary connection with a floor, a guide-arm extending from the stand, a carrier in spring-controlled sliding engagement with the arm, means for latching the carrier in retracted position against spring-resistance, a spittoon having a slide attachment engaging said carrier against a stop therewith, and a swing-stop in connection with the aforesaid carrier forward of the spittoon.

In testimony that we claim the foregoing we have hereunto set our hands at Milwaukee in the county of Milwaukee and State of Wisconsin in the presence of two witnesses.

FRANK SOCHUREK, JR.
JOSEPH SOCHUREK.
